Fig. 4.

A technical line drawing of a mechanical component. A central vertical rod has a horizontal slot cut into its side. A curved support arm, labeled with the number 8, is attached to the top of the rod. A vertical support, labeled with the number 10, is attached to the bottom of the rod. A base, labeled with the number 19, is attached to the bottom of the vertical support. The entire assembly is shown within a rectangular frame.

UNITED STATES PATENT OFFICE.

BRUCE M. UMHOLTZ, OF WAMEGO, KANSAS

CONTAINING AND DISPENSING DEVICE.

1,071,482.

Specification of Letters Patent. Patented Aug. 26, 1913.

Application filed August 31, 1912. Serial No. 718,093.

To all whom it may concern:

Be it known that I, BRUCE M. UMHOLTZ, a citizen of the United States, residing at Wamego, in the county of Pottawatomie and State of Kansas, have invented new and useful Improvements in Containing and Dispensing Devices, of which the following is a specification.

This invention relates to a containing and dispensing device or vessel designed especially for the use of dentists for the purpose of holding and dispensing plaster of Paris, investment compounds, and other substances and compositions customarily employed in dental work, the object of the invention being to provide a device of this character whereby a compound or substance may be loosened up and dispensed in any quantity desired, whereby two or more compounds may be contained and dispensed within and from the same vessel, and whereby the contained materials may be inclosed and protected from the atmosphere and the access of foreign materials.

The invention consists of the features of construction, combination and arrangement of parts hereinafter fully described and claimed, reference being had to the accompanying drawings, in which:

Figure 1 is a front elevation of a containing and dispensing vessel embodying my invention. Fig. 2 is a side elevation of the same. Fig. 3 is a vertical section on the line 3—3 of Fig. 1. Fig. 4 is a vertical section on the line 4—4 of Fig. 2. Fig. 5 is a top plan view of the vessel with the cover removed. Fig. 6 is a detail view of the cover. Fig. 7 is a detail view of the agitator. Fig. 8 is a longitudinal section through one of the feed devices. Fig. 9 is a detail section on the line 9—9 of Fig. 1.

Referring to the drawings, 1 designates the dispensing vessel, which preferably is of rectangular form and provided with a tapering or frusto-conical lower end 2. This vessel is provided with a suitable cover or lid 3 having a depending flange 4 to fit airtight therein, a portion of said flange being cut away, as at 5 shown in Fig. 6, for a purpose hereinafter described.

The body of the vessel 1 is designed to contain plaster of Paris or other material to be stored or dispensed, and in practice the vessel and its cover are made of galvanized iron or other suitable material in which various substances may be stored without injury

thereto or to the vessel. The tapered lower end of the vessel is provided with a discharge slot or outlet 6 and contains an agitator 7 consisting of a horizontal shaft 8 extending transversely through and journaled in the walls of the tapered portion of the vessel and carrying a series of radial agitator blades 9, whereby the plaster of Paris or other material to be dispensed may be loosened by the agitator and discharged in a properly loosened condition through the slot 6. The slot 6 communicates with a feed tube or cylinder 10 in which is journaled a shaft 11 carrying a feed screw 12. One end of the cylinder is provided with a fixed wall 13 in which one end of said shaft 11 is journaled, while the other end of the cylinder is threaded to receive a screw cap 14 in which the opposite end of the shaft 11 is journaled, the construction being such that upon the removal of the cap the feed device as a whole may be withdrawn from the tube or casing to enable the same to be cleaned or repaired to be readily made. On the adjacent ends of the shafts 8 and 11 are gears 15 and 16, and on one end of the shaft 11 is a crank handle 17 whereby the feed device may be rotated and the agitator simultaneously rotated as a result of which the material in the vessel will be properly loosened up, fed through the slot 6 into the cylinder, and then discharged in proper quantity for use through an outlet 18 at one end of the cylinder by the feed screw.

Arranged within the upper portion of the vessel 1 is an internal vessel or compartment 19, whose mouth or upper end is flush with the mouth of the vessel 1 and whose rear wall preferably inclines downwardly and forwardly to provide a contracted lower end having a discharge slot 20. Communicating with this discharge slot is a feeder similar in construction to that before described, said feeder comprising a cylinder 21 having a fixed end 22 in which is journaled one end of a shaft 23, the opposite end of which is journaled in one of the side walls of the vessel 1 and provided at its outer end with an operating crank 24. The shaft 23 carries a feed screw 25 and the cylinder is provided at its discharge end with an outlet tube 26 which projects to the exterior through the front wall of the vessel 1. This internal compartment may contain investment compounds or other substances commonly kept in small quantities and dispensed at intervals for use, and if desired the vessel and

internal compartment may contain substances of different character commonly kept and combined in different quantities and which may be individually dispensed at the time of use. For instance, plaster of Paris may be kept in the compartment 1, and marble dust or other material in the compartment 19, and dispensed for admixture in the production of an investment 10 pound when occasion requires. That portion of the cover 3 from which the flange 4 is cut away is designed to close the top of the compartment 19, while the flange fits within and closes the top of the vessel 1, thus sealing both the internal compartment and body of the vessel against the access of moisture, dirt and other foreign materials.

In practice, the device may be provided with suitable means for suspending it from 20 a wall or other support so that it may be conveniently filled and its contents readily and conveniently dispensed.

I claim:—

A containing and dispensing device comprising a vertically disposed receptacle of 25 rectangular form and provided with a bottom having downwardly converging side walls, and rear walls downwardly converging at their upper ends and curved at their 30 lower ends to provide a partially cylindrical chamber provided at the point of conver-

gence of said walls with an outlet, a shaft journaled in the converging side walls of the chamber and carrying a gear at one end thereof, a bladed agitator mounted upon 35 said shaft to rotate within said chamber, a casing on the exterior of and extending transversely of said receptacle and communicating centrally with said outlet, said casing being coextensive in length with the 40 width of the receptacle and having a fixed wall and a depending outlet at one end and being open at its opposite end, a detachable closure for the open end of said casing, a shaft of greater length than the discharge 45 outlet and extending longitudinally within the casing and journaled at its opposite ends in the said fixed end wall and removable closure of said casing, a feed screw carried by said shaft, a gear upon one end 50 of said shaft meshing with the gear upon the agitator shaft, and an operating device connected with the feed screw shaft, said shaft, screw and associated gear being removable from the casing with the closure 55 when the latter is detached.

In testimony whereof I affix my signature in presence of two witnesses.

BRUCE M. UMHOLTZ.
